UNITED STATES PATENT OFFICE.

WILLIAM RICHARD WHITE, OF BLOOMINGTON, ILLINOIS.

GATE.

SPECIFICATION forming part of Letters Patent No. 654,210, dated July 24, 1900.

Application filed August 24, 1899. Serial No. 728,350. (No model.)

To all whom it may concern:

Be it known that I, WILLIAM RICHARD WHITE, a citizen of the United States, residing at Bloomington, in the county of McLean 5 and State of Illinois, have invented certain new and useful Improvements in Gates, of which the following is a specification.

This invention relates to certain new and useful improvements in swinging gates, and 10 particularly to the connections between the opposing ends of the operating-levers employed to open and close the gate; and it consists, substantially, in such features of construction, arrangement, and combination of 15 parts as will hereinafter be more particularly described.

The invention is fully illustrated in the accompanying drawings, in which—

Figure 1 represents a view in perspective 20 of a swinging gate having my improvements embodied in connection therewith. Fig. 2 is a side view, partly in section, of portions of the operating-levers, showing one form of my improved connecting devices. Figs. 3 and 4 25 are similar views showing other forms of connecting devices in which the principle of my invention is embodied.

In the drawings, 1 indicates the gate, which may be of any ordinary construction; 2, the 30 post, upon which the gate is supported by means of suitable hinges 3 3; and 4, the post on the opposite side of the gate-opening against which the gate closes.

5 is a post in alinement with post 2 on the 35 same side of the roadway, and 6 is a post set adjacent to post 5 and against which the gate may be carried. Posts 5 and 2 are preferably connected at their upper ends by a cross-bar 8.

The operating-levers are designated by 40 9 and 10, the former being pivoted between its ends on the post 5 and the latter on a block or bar 11, extending diagonally from the post 2 and secured thereto and to the cross-bar 8. The levers are so formed and pivoted that 45 their inner or adjacent ends normally tend to swing downwardly.

The gate in the present instance is shown as provided with a longitudinally-sliding latch-bar 12, provided at its forward end with 50 a rectangular loop 13 for engaging keepers 14 on posts 4 and 6. The bar 12 is actuated by

a combined rocking and oscillating lever 22, suitably supported on the gate and connected by a link 30 to the lever 10.

The foregoing construction forms no part 55 of the present invention and is very similar to the constructions set forth in some of the patents heretofore granted to me.

Referring now to Fig. 2, it will be seen that the inner end of the lever 10 is provided with 60 a longitudinally-extending hole 35, which may be bored with an auger or otherwise formed. In this hole a rod 36 is loosely fitted to slide longitudinally therein. The inner end of the lever 9 is vertically slotted, as shown at 37, 65 and the rod 36 projects into this slot and is formed with an eye 38, and a pin 39, secured in the lever 9, extends through the eye and forms a pivot upon which the rod may swing vertically. By this means the levers are so 70 connected that they may swing freely on their pivots and the movement of one lever will impart a like movement to the other lever with a minimum of lost movement. The connection also tends to prevent lateral move- 75 ment of the levers, and the guides which are usually employed to prevent lateral movement of the levers in this class of gates may be dispensed with. It is of course obvious that the hole 35 may be enlarged and a metal 80 tube of sufficient internal diameter to receive the rod 36 be fitted therein.

In Fig. 3 the construction is similar except that the end of the rod 36 is forked, as indicated at 40, and straddles the lever, the pivot- 85 pin 39 passing through both prongs and the lever, and the slot in the latter is omitted.

In Fig. 4 is shown a construction which effects the same results. Here the rod 36 is pivotally connected to the lever 9 in the same 90 manner as in Fig. 2; but in the end of lever 10 two eyebolts 42 42 are secured in position with their eyes in alinement, and the rod 36 slides in these eyes. One way to insert the eyebolts 42 is to cut transverse openings in 95 the lever of a size sufficient to permit the passage of the enlarged or eye portion of the bolts from one side of the lever. Such openings may be of a uniform size entirely through the lever or they may be reduced in size on 100 one side of the lever beyond where the eye portion rests to receive the bolt beyond the

eye portion on that side. When the nuts are tightened up the eyebolts will be securely held in either case.

It is obvious that the invention may be embodied in many other forms, and hence I do not limit myself in its embodiment to the constructions illustrated.

Having described my invention, I claim—

1. The combination of two gate-operating levers, and a rod pivotally attached to one lever and mounted on the other so as to slide longitudinally thereon.
2. The combination of two gate-operating

levers, one of which is provided with a longitudinally-extending hole at one end, and a rod pivotally attached to the other lever and extending into said hole to slide longitudinally therein, substantially as set forth.

In testimony whereof I have signed my name to this specification in the presence of two subscribing witnesses.

WILLIAM RICHARD WHITE.
